(57) CLAIM

The ornamental design for an “ice bucket,” as shown and described.

DESCRIPTION

FIG. 1 is an elevated perspective view of the ice bucket showing my new design;

FIG. 2 is a front plan view thereof;

FIG. 3 is a side plan view thereof;

FIG. 4 is a top plan view in the closed position thereof;

FIG. 5 is a top plan view thereof;

FIG. 6 is an elevated perspective view of the liner;

FIG. 7 is a side plan view of the liner;

FIG. 8 is a top plan view of the liner;

FIG. 9 is a bottom plan view of the liner;

FIG. 10 is an elevated perspective view of the lid;

FIG. 11 is a plan view of the top of the lid;

FIG. 12 is a plan view of the bottom of the lid;

FIG. 13 is a plan side view of the lid; and,

FIG. 14 is a top perspective view of the bucket, liner and lid. The bucket, liner and lid are shown separately for clarity of illustration.
